WASHINGTON IRVING MIDDLETON, OF WATERTOWN, MASSACHUSETTS, ASSIGNOR TO
SIMPLEX WIRE AND CABLE COMPANY, OF BOSTON, MASSACHUSETTS, A CORPOR-
ATION OF MASSACHUSETTS

TELEPHONE PLUG CORD

Application filed July 25, 1928. Serial No. 295,331.

This invention relates to improvements in multi-conductor cables used to connect pairs of jack plugs in the conventional telephone switchboard. These cables are commonly 5 designated telephone plug cords. The conventional cable now used for this purpose consists of three conducting elements each made up of a number of strands of tinsel on a cotton core enclosed within a silk wind and 10 a braided jacket, the three conducting elements together with suitable fillers being enclosed within a common outer braided jacket. This conventional cable has two serious disadvantages; it is expensive and it is of relatively short useful life. Replacement of such 15 cable is frequently necessary as often as ten or twelve times a year on busy switchboards. In such service the saving in operating expense possible by reducing the number of such 20 placements exceeds any saving possible in reducing the cost of the cable. The improved telephone plug cord of the present invention is less expensive than the conventional type of cord and it has the important advantage of 25 having a useful life exceeding fourfold or more the usual life of the conventional type of cord.

Cables embodying the invention are illustrated in the accompanying drawings and 30 the invention will be described in detail in connection therewith. In the accompanying drawings

Fig. 1 is a fragment of one form of cable embodying the invention with parts broken 35 away and Fig. 2 is a section of the cable shown in Fig. 1, and

Fig. 3 is a fragment of another form of cable embodying the invention with parts broken away and Fig. 4 is a section of the 40 cable shown in Fig. 3.

Referring to Figs. 1 and 2, the cable comprises three conducting elements 5, 6 and 7, three filler elements 8, 9 and 10, a binder 11 and a jacket 12. Each of the conducting elements 5, 6 and 7 comprises a non-conducting core 13 of soft fibrous material, a plurality of conducting wires 14, small in diameter with respect to the core 13, wound about the core in a short spiral, 8 to 10 turns per inch 50 for example, a non-conducting winding 15

and a braided jacket 16. For example, the core 13 may be of 6/9 loom yarn, the conducting wires 14 may be of a group of six strands of #34 (B. & S. gauge) copper, the winding 15 may be of cotton saturated with a mixture 55 of 50% stearine pitch and 50% paraffine wax, and the jacket 16 may be a 26/2 soft cotton braid. The filler elements 8, 9 and 10 may be of cotton yarn and the binding 11 of the usual binding string. The outer jacket 12 is of 60 elastic vulcanized rubber compounded to afford a maximum of physical strength and resistance to abrasion. Compounds of the type used as automobile tire tread stocks are useful in this connection. A suitable rubber compound, for example, may consist of the following:

	Parts
Rubber (smoked sheets)	63
Zinc oxide	9 70
Carbon black	24
Ozokerite	2
Ethylidene-aniline	1/2
Di-phenyl-guanidine	1/2
Sulphur	3 75
	—
	102

This compound may be vulcanized at 270° F. for 30 minutes. The rubber jacket 12, for example, may be of 0.022"-0.034" in thickness. These cables are finished to an outer diameter of 0.280".

Referring to Figs. 3 and 4, the cable is of construction identical with that illustrated in Figs. 1 and 2 except in that a braided jacket 17 is interposed between the outer rubber jacket and the bound group of conducting elements and filler elements. This interposed jacket 17 may be a 40/2 soft cotton braid, for example. This interposed braided jacket further improves the flexibility of the complete cable.

In each of the cables just described in detail the conducting elements and the filler elements, the latter being small with respect to the former, are spiralled together and bound to form a strong yet flexible composite. The conducting elements and filler elements are bound together independently of the encas-

ing rubber jacket. Within this composite the construction of the individual conducting elements provides the requisite flexibility. The conducting wires are wound on the core 5 in a short spiral and, with advantage, are arranged in a spiralled group with successive turns of the group spaced from the preceding turns. This particular construction makes possible the use of wire as the conducting element instead of the usual tinsel. This composite, then, encased within the outer elastic vulcanized rubber jacket is protected against mechanical disturbance and, with the added strength of a rubber jacket of the 10 type specified, provides a complete cable of unusual life yet having all of the other properties requisite to this class of service and at the same time relatively inexpensive.

I claim:

- 20 1. An improved telephone plug cord, consisting of a plurality of conducting elements and a plurality of filler elements small with respect to the conducting elements spiralled together and encased in an outer jacket of 25 elastic vulcanized rubber, said spiralled conducting elements and filler elements being bound together independently of the encasing jacket, said conducting elements each consisting of a non-conducting core, a plurality of 30 conducting wires small with respect to the core wound thereon in a short spiral, a winding of non-conducting material thereover and an encasing braided jacket.
- 35 2. An improved telephone plug cord, consisting of a plurality of conducting elements and a plurality of filler elements small with respect to the conducting elements spiralled together and encased in an outer jacket of elastic vulcanized rubber, said spiralled conducting elements and filler elements being bound together independently of the encasing jacket, said conducting elements each 40 consisting of a non-conducting core, a plurality of conducting wires small with respect to the core wound thereon in a short spiral, a winding of non-conducting material thereover and an encasing braided jacket, said plurality of conducting wires arranged in a 45 group with successive turns of the group spaced from preceding turns.

In testimony whereof I affix my signature
WASHINGTON IRVING MIDDLETON.
